UNITED STATES PATENT OFFICE

CLARICE E. HEILBRON, OF BELVEDERE, CALIFORNIA

DESIGN FOR A DOLL

Application filed August 24, 1931. Serial No. 40,915. Term of patent 7 years.

To all whom it may concern:

Be it known that I, CLARICE E. HEILBRON, a citizen of the United States and a resident of Belvedere, county of Marin, State of California, have invented a new, original, and ornamental Design for a Doll, of which the following is a specification, reference being had to the accompanying drawings, forming part thereof.

Referring to the drawings:

I claim:

The ornamental design for a doll as shown.

CLARICE E. HEILBRON.
